SPAGHETTI FORK

Malcolm R. Braid, 1005 Cumberland Drive,
Auburn, Ala. 36830

Filed Oct. 19, 1973, Ser. No. 408,154

Term of patent 14 years

Int. Cl. D7—03

U.S. Cl. D7—137

FIG. 1 is a top perspective view of a spaghetti fork showing my new design;

FIG. 2 is an inverted side elevational view thereof;

FIG. 3 is a left end elevational view thereof;

FIG. 4 is a top plan view thereof; and

FIG. 5 is a view similar to FIG. 4 illustrating the environmental use of the spaghetti fork in broken lines.

I claim:

The ornamental design for a spaghetti fork, as shown and described.
